UNITED STATES PATENT OFFICE

CURT W. KLOSTERMANN, OF CHICAGO, ILLINOIS, ASSIGNOR TO SMOKETERIA INCORPORATED, OF CHICAGO, ILLINOIS, A CORPORATION OF ILLINOIS

SLUG EJECTOR

Application filed March 2, 1929. Serial No. 343,900.

This invention relates to a slug ejector. It is designed for use in connection with a coin or token operated or controlled device. It has for its general object to eject coins or tokens which are not of the proper size, shape or weight or are otherwise of an unsuitable character for reception into the machine. Other objects will appear from time to time in the course of the specification and claims.

The invention is illustrated more or less diagrammatically in the accompanying drawings wherein:

Figure 1 is a side elevation;

Figure 2 is a transverse vertical cross section taken on line 2—2 of Figure 1;

Figure 3 is an end elevation looking in the direction of the arrow as indicated in Figure 1.

Like parts are designated by like characters throughout the specification and drawings.

A is a plate provided on one side with an inclined flange A¹ which may be notched as at A², A³. The plate has preferably formed integrally with it a generally curved enlargement or thickened part A⁴. In the form here shown this part conforms generally to the outline of a coin vending machine with which the slug ejector is associated. That portion of the slug ejector lying generally below the flange A¹ is within the body of the machine and that portion of the slug ejector lying generally above the flange A¹ is outside of the machine or normally projects upwardly from it. The plate A is provided with a laterally extending overhanging flange A⁴.

A⁵ is an opening formed in the plate A. A⁶ is a magnet removably held in position by means of the screw A⁷ and the washer A⁸. A⁹ is a boss formed on the plate A and adapted to have positioned upon it a bearing supporting plate A¹⁰ which is pivotally mounted as at A¹¹ and is provided with a slot A¹² in its larger end. A¹³ is a screw extending through the slot A¹² and positioned in the plate A, by means of which the bearing supporting plate A¹⁰ may be moved and supported in adjusted position. A¹⁴ is a curved slot in the plate A through which a bearing or pin A¹⁵ projects into the interior of the slug ejector.

An irregularly shaped passage is formed within the plate A. It consists of the portion B which in one form of the invention is directed generally down so that it adjoins an inclined straight portion B¹ which joins it at an angle. At its lower end the portion B¹ which communicates with a curved portion B² which finally communicates with an enlarged space or passage B³ which is open at its bottom as at B⁴. Formed in the sides of the passage are a plurality of grooves or extended depressions B⁵, B⁶. They are separated by a land or raised portion B⁶ which extends with them throughout the length of the passages B¹ and B².

C is a coin controlling lever balanced on the bearing A¹⁵ and lying within the enlarged space B³. It is provided at its lower end with a weighted portion C¹ and at its upper end with a curved coin contacting arm C².

D is a plate somewhat similar to the plate A. It is provided with a flange D¹ and has in its inner face grooves D² corresponding to the grooves B⁵, B⁶ in the plate A and positioned oppositely to them when the parts are assembled as shown in Figure 2. The grooves D² are separated by a raised portion or land D³ which corresponds to the similarly raised portion or land B⁶ formed in the inner face of the plate A. At its bottom adjacent the opening B⁴, the plate D is provided with a laterally inclined flange D⁴ and it has secured to it a slug guiding member D⁵ which is provided with an inclined portion D⁶ and guiding and limiting wings D⁷. It is fastened to the plate D by means of screws D⁸.

E is a plate positioned upward of the plates B and D where they join and it overlies both of them. It is provided with a slot E¹ to permit the introduction of a coin or token and is removably held in position by screws, E².

It will be obvious that while I have shown and described an operative device, many changes may be made in the size, shape, number, relation and distribution of parts without departing from the spirit of my invention, and I wish therefore, that my description and showing be considered as in a large measure diagrammatic.

The use and operation of this invention are as follows:

When a coin or token of the proper size, shape and weight is inserted in the slot E¹ it moves more or less vertically downwardly through the short, generally vertical disposed passage B. It then strikes the flat inclined bottom of the passage B¹ and rolls along this to the right, as shown in Figure 1. The cut 10 away portions of the sides of the passage B¹, that is to say, the grooves B⁵, B⁵ and D², D² serve to reduce the friction and probably the jamming of the coin. When the coin reaches the end of the flat portion of the bottom 15 of the passage B¹, it drops off into the reversely curved passage B². Normally it flies clear across this passage and strikes the right hand or outer wall of the passage B². Its rotation is then reversed and it rolls down 20 the curved bottom of the passage B² past the slot A⁵ and the magnet A⁶. It jumps off the end of the curved bottom part of the passage B², emerges into the enlarged chamber B³ and strikes the upper portion C² of the lever 25 C. Since its weight, size and shape are proper, it will strike with sufficient force to overbalance the lever. It will raise the weighted end C¹ of the lever sufficiently to permit it to fall off the left of the upper end C². It then 30 passes outward through the opening B⁴ and into the coin controlled or coin operated mechanism with which the slug ejector is associated. These parts are not here shown as 35 they form no particular part of the present invention since the slug ejector may be associated with a variety of other mechanisms. If the coin is not of the right size or shape or weight, if for example, it is of a metal responsive to the magnet or if it is too light, 40 it will not move with sufficient force to clear the space between the end of the bottom of the curved passage B² and the lever C². It will not pass on into the mechanism but will be ejected through the slug ejector. Even if 45 it does reach this part of the machine with such force to clear the space and to strike the member C² if it does not strike this member with a force sufficient to rotate it so as to permit the coin to be discharged to the left over 50 the end C² of the lever, it will nevertheless fall backward into the passage X and be discharged out of the machine through the slug ejecting passage X¹ and the chute D⁶. 55 Where in the specification and claims I have used the word coin or token, I do not wish to be limited to either of these. It is therefore understood that where the device is applied to a coin operated or coin controlled mechanism, normally the coin or some special 60 form of slug or token will be used. It is the purpose of the method and apparatus of this machine to eject coins and tokens or slugs which are not of the proper size, shape and weight. The mechanism is adjustable and 65 when adjusted normally, it is arranged to

operate with a particular size and shape of coin, slug or token. It is therefore arranged to reject others which do not come up to the standards set up at the time the machine is adjusted. The invention, however, is not 70 particularly limited to this feature and may be used for the classification of other objects whether or not it is associated with a coin operated mechanism.

I claim:

1. In a token classifier, an inclosure defining a tortuous passage terminating in substantially a horizontal position and a chamber to which said passage leads, a movably mounted element within said chamber, said passage so shaped that a token deposited within it moves through it under the influence of gravity alone, is projected generally laterally across the chamber under the influence of its momentum solely and against the 85 movable element, said movable element so mounted and being of such weight that a coin striking it with more than a given force will move it sufficiently to pass beyond it and a coin striking it with less than a given force 90 will fail to pass beyond it.

2. In a token classifier, means for classifying the tokens according to weight, including an inclosure defining a tortuous passage into which the token may be introduced and along which it is adapted to move, the passage so shaped as to compel the token as it rolls to move through it under the force of gravity alone and to cause the token to rotate first in one direction and then in another 100 during its passage, means for subjecting the token to a magnetic influence as it moves through the passage, and means for projecting it across a space under the influence of its momentum solely, there being in combination 105 with the passage a chamber within which is located a movable element against which the token is projected, said element adapted to be moved more or less by the token as it is contacted, the degree of such movement depending upon the force with which it is struck and affecting the classification of the token.

3. In a token classifier, an enclosure defining reversely directed substantially horizontal passages, a chamber to which one of said passages leads, a movable member mounted in said chamber and spaced from the one end of one of the substantially horizontal passages, said passages and movable member being so positioned that a coin traversing said chutes will contact said movable member under the influence of its momentum with such force as to pass over said member or fail to pass the same.

Signed at Chicago, county of Cook and State of Illinois, this 28th day of February, 1929.

CURT W. KLOSTERMANN. 130
